SWIMMING DEVICE

Lawrence P. Romano, Los Angeles, Calif.

Application May 13, 1949, Serial No. 2,640

Term of patent 14 years

(Cl. D71—1)

To all whom it may concern:

Be it known that I, Lawrence P. Romano, a citizen of the United States, and a resident of Los Angeles, California, have invented a new, original, and ornamental Design for a Swimming Device, of which the following is a specification, reference being had to the accompanying drawing, forming part thereof.

Referring to the drawing:

Figure 1 is a perspective view of a swimming device, showing my new design;

Figure 2 is a top plan view of the device;

Figure 3 is a bottom plan view thereof;

Figure 4 is a side elevational of the device, as seen in the direction of arrow 4 of Figure 2;

Figure 5 is a front elevation of the device; and

Figure 6 is a rear elevation thereof.

I claim:

The ornamental design for a swimming device, as shown.

LAWRENCE P. ROMANO.
